UNITED STATES PATENT OFFICE

96,774

DESIGN FOR AN ASH TRAY OR SIMILAR ARTICLE

William Nuzum, New York, N. Y.

Application October 25, 1934, Serial No. 53,754

Term of patent 3½ years

To all whom it may concern:

Be it known that I, William Nuzum, a citizen of the United States and a resident of the city of New York, Borough of Manhattan, in the county of New York and State of New York, have invented the new, original, and ornamental Design for an Ash Tray or Similar Article, of which the following is a specification, reference being had to the accompanying drawing, forming part thereof, wherein an essential feature is the inverted, substantially U-shaped support arranged within a holding tray, and in which

Figure 1 is a perspective view of an ash tray showing my new design, and

Figure 2 is a sectional view through Figure 1, illustrating the ornamental arrangement of the base and overhanging portion interior of the base.

I claim:

The ornamental design for an ash tray or similar article, substantially as shown and described.

WILLIAM NUZUM.
